UNITED STATES PATENT OFFICE.

JOSEPH E. TYNAN, OF PATERSON, NEW JERSEY.

DOUBLING AND WINDING MACHINE.

SPECIFICATION forming part of Letters Patent No. 422,667, dated March 4, 1890.

Application filed February 20, 1889. Serial No. 300,564 (No model.)

To all whom it may concern:

Be it known that I, JOSEPH E. TYNAN, of Paterson, in the county of Passaic and State of New Jersey, have invented an Improvement 5 in Doubling and Winding Machines, of which the following is a specification.

My invention relates to doubling, twisting, and analogous machines in which a number of single threads are drawn from bobbins 10 and doubled together and placed upon a single bobbin; and it consists, first, in mechanism for gripping the winding-spindle pulley and stopping it when a thread breaks; secondly, in means for giving tension to the 15 single threads as they are drawn off from stationary bobbins; thirdly, in a pair of rollers between the fallers and the feed-roller to hold a broken end, so that it may be readily pieced.

The threads are drawn from the heads of 20 the bobbins, which stand upright on a creel in the front part of the machine. They then pass around tension-fingers, then up and through the fallers of the stop-motion, and against a guide and over a guide-roller placed 25 high up on the machine. From there the threads come down to a guide behind the feed-roller, then around the feed-roller, and from there downwardly through a guide-eye to the receiving-bobbin on the spindle.

30 In the drawings, Figure 1 is an elevation of the doubling and winding mechanism, the rails being in section. Fig. 2 is a plan view, in larger size, of one group of bobbins and the driving mechanism, the winding-spindle being in section. Fig. 3 is an elevation of the 35 same; and Fig. 4 is a plan view below the line $\alpha\alpha$, Fig. 5. Fig. 5 is an elevation illustrating the positions of the feed and driving rollers and fallers. Fig. 6 is an elevation, in larger size, of the guide and presser rolls, the 40 bearings being in section. Fig. 7 is an elevation illustrating the direction in which the threads pass, and Fig. 8 is a detached view of the creel-bracket.

45 Reference is hereby made to my application, Serial No. 256,728, filed December 2, 1887, and patented February 19, 1889, for a description of the stop-motion that is applicable to my present invention, and which corresponds, except in the particulars hereinafter named, to the device therein shown for stopping the ro-

55 tation of the spindle and of the winding and feeding mechanism when one of the threads breaks, and in my present application the same figures are made use of in referring to the parts that correspond to those in my said patent.

The threads to be doubled and wound are supplied from bobbins a a . I have shown three of such bobbins as resting upon a bracket 6c or creel b , that projects from the spindle-rail B , and above the bobbins a is a stationary bracket or arm c , upon which the tension-fingers c' are supported. These tension-fingers are preferably made of L-shaped wires, the 65 finger portions projecting downwardly and there being eyes at the opposite ends of the wires for the screws c^2 , by which the fingers are attached to the bracket c , and there are stops c^3 upon the brackets for holding the 70 fingers in their proper position centrally over the stationary bobbins a . I have provided for allowing such fingers to be turned or moved aside into the position represented by dotted lines in Fig. 2, for a purpose hereinafter 75 named. The wire composing each finger is sufficiently elastic to allow it to be sprung out of the latch portion of the stop and then swung aside upon its screw c^2 into the position indicated by dotted lines, Fig. 2, the important feature in this connection being that the hinged finger can be turned out of the way in removing the bobbin, and when swung back to position it is centrally over the bobbin. 80

85 The bobbins a rest upon the creel b , and there are upwardly-projecting pins for holding the bobbins in their positions; but these pins are comparatively short, so that there is room above the bobbins for lifting them off 90 the pins when any one bobbin is exhausted and for placing in position another bobbin; but to facilitate this operation, as the ranges of bobbins are comparatively near each other, as indicated in Fig. 2, the inner L-shaped 95 fingers c' can be swung aside, so that the bobbins can be moved vertically as one bobbin is lifted off and another introduced in its stead.

100 The creel or bracket b has a foot-piece b^3 resting against the side and bottom of the spindle-rail B , and there is a hole for the bot-

tom of the spindle-socket b^4 to pass through, and the nut b^5 , that holds the spindle-socket, also holds the bracket or creel. This facilitates the construction and the placing together of the parts, and the arm c extends upwardly from the foot of the creel.

In my said patent I have represented fingers around which the thread is twisted as it is drawn off, the twisting being effected by 10 the rotation of the supply-bobbins. In my present invention the supply-bobbins remain stationary; but in consequence of the fingers c' being comparatively close to the upper ends of such bobbins each thread is twisted 15 around its finger in consequence of such thread describing a circular path around the head of the bobbin as such thread is pulled rapidly over the bobbins by the winding apparatus, hereinafter described; hence the fingers c' act as tension devices, and at the same time form guides to maintain the threads in the proper positions. The threads pass upwardly and in front of thread-guides 35, and between such thread-guides are the hooks 20 of the faller-wires 37, each thread passing through its appropriate hook, and the faller-wire, when a thread breaks, falls backwardly instead of forwardly, as in my said patent. I provide three faller-wires where there are 25 three bobbins a , and the number is to be increased to correspond to the number of bobbins. Each faller-wire 37 has a finger 62, coming into contact with the rocking lever 65 to lift the same and bring the claw 69 into 30 one of the recesses 74 of the driving-roller 13 upon the shaft 14, so that said roller 13, acting upon the claw 69, swings the rocking lever 65, and the end thereof pushes the latch 40 off the back edge of the faller-stand, so that 35 the link 50 allows the belt-lever 33 to descend and slacken the belt 30, and after the thread has been pieced or mended the parts are restored to their normal position, as described in my aforesaid patent.

40 The belt 30 in my present invention is only employed to drive the winding-spindle and pulley 93 and the receiving-bobbin 8, and I make use of a toe i upon the lever 33 to act below the pulley 93 to apply friction directly 45 to the same to stop the revolution thereof when either faller-wire 37 acts to allow the lever 33 to descend, as before described, and in order to clamp this pulley 93 firmly I provide a stationary finger i' , that extends up 50 above the pulley, so as not to be in contact therewith except when the lever 33 descends and the toe i slightly raises the pulley 93. In this manner the winding operation is arrested instantly, which is of great importance, 55 because the winding operation in my improvement is so rapid that when the receiving-bobbin is allowed to revolve after either faller-wire comes into action the end of the 60 broken thread might be in a position not easy of access.

In order to expose the separate threads for a long distance and in a position easily ac-

cessible to the attendant, I carry such threads up above the thread-guides 35 to the guide-roller d , which is upon a standard d' and not 70 too high to be easily reached by the attendant. This guide-roller d is in a bearing d^2 , that is below the roller, so that there is nothing to interfere with the attendant passing the threads over such guide-roller d , and above the guide-roller is a presser-roller e , that is shorter than and rests upon such guide-roller d , and is held in a bearing that passes above it, as shown in Fig. 6, so that 75 the threads upon the roller d draw in automatically below the roller e by the tension on the threads, and there is a guide pin or eye e' upon the bearing d^2 , against which the threads draw as they pass up to and over the guide-roller d , and from the guide-roller d the 80 three or more threads pass down together through the guide or eye a^6 , and from there they pass around the feed-roller 11 and through the detector 64 and the stationary guide-hook 82 down to the receiving-bobbin 90 8, as in my said patent. It will now be apparent that the hooks upon the three faller-wires 37 guide the threads as they pass upwardly from the stationary bobbins a and fingers c' , and that after passing through 95 such faller-hooks 37 the threads converge to the guide-pin e' , and should one of the threads break the faller-wire and stop-motion will arrest the winding mechanism in most instances before the broken end reaches 100 the presser-roller e ; hence such end is held by the presser-roller e and is not liable to become entangled with any of the adjacent threads, and can easily be pieced to the end of the thread from another bobbin or the 105 ends of the broken thread joined together, and this presser-roller e maintains a slight tension upon the threads as they pass down to the guide a^6 , even when all of the supply-threads may become more or less loosened 110 in piecing or mending any of the threads passing from the supply-bobbin, and should either of the said threads be unusually large at any place the weight of the presser-roller e will rest principally upon such large thread, 115 and the tension in turning the guide-roller and presser-roller will be principally upon such large thread. There will be a unifying or equalizing action that tends to compensate a difficulty heretofore experienced in 120 doubling-machines—namely, that the smaller thread is liable to be stretched in drawing it through the various guides, and it will contract and render the larger thread loose when the threads are unwound from the lay-up 125 bobbin. The guide a^6 is preferably upon a traverse-bar 24, as in my said patent, for varying the position or lead of the threads as they pass around the feed-roller 11.

I have shown in Fig. 1 a convenient means 130 for driving the shafts 14 and for varying the speed of such shafts in relation to the main shaft 1 and the receiving-bobbins 8. In this mode of driving the belt k passes from a pul-

ley k' on the shaft 1 over the pulleys l l' to drive the respective shafts 14, the pulley being upon the end of one shaft 14 and there being gears 15 between the pulley l and the other shaft 14, in order that such second shaft 14 may be driven in the proper direction for the sets of bobbins and the driving-rolls upon the other side of the machine, and the tightener-pulley m is upon a gudgeon 5 that is adjustable in a slot in the frame A of the machine, and this not only allows for tightening the belt, but it also allows for a different-sized pulley k' to be placed upon the shaft 1 for varying the speed of the belt and 10 of the driving-rolls that receive motion from this belt, whereby the twist given to the threads as they are led upon the receiving-bobbins 8 can be varied.

I claim as my invention—

- 20 1. The combination, with the creel or support upon which two or more stationary bobbins are to be placed, of a downwardly-projecting tension-finger centrally above each bobbin, the feed-roller for drawing off the threads, a spindle for the bobbins upon which the doubled threads are to be wound, and a stop mechanism for arresting the feed-roller and the winding-spindle in case of the thread breaking, substantially as set forth.
- 25 2. The creel or support for stationary supply-bobbins, in combination with stationary downwardly-projecting fingers centrally above the respective bobbins, and around which the threads are wrapped by the circular movements of the threads as drawn off from the bobbins, and a feed-roller for drawing off the threads, substantially as specified.
- 30 3. The combination, with the creel or support for stationary bobbins, of a feed-roller, a 40 faller for each thread, a stop mechanism acted on by the faller, and an elevated guide-roller, over which the threads pass from the faller-wires to the feed-roller, and a presser-roller above the guide-roller, substantially as set forth.
- 35 45

4. The combination, with the feed-roller and the fallers for each thread, of a guide-roller in an elevated position, over which the threads pass, and a presser-roller resting upon the threads and guide-roller, substantially as 50 and for the purposes set forth.

5. The combination, in a winding mechanism, with the feed-roller, of a guide-roller d and the presser-roller e to bear upon the threads as they pass over the guide-roller, the 55 guide-roller being in open bearings and larger than the presser-roller to allow for the insertion of the threads, substantially as set forth.

6. The combination, with the creel or support for a group of supply-bobbins, of a downwardly-projecting tension-finger centrally 60 over each bobbin and a support for the tension-finger above and at one side of the bobbins, the tension-fingers being movable to allow for placing or removing the bobbins, substantially as set forth.

7. The combination, with the winding-spindle and its pulley and driving-band, of a lever and pulley for tightening the band to the spindle-pulley, a toe upon the tightening-lever acting at one side of the spindle-pulley, and a stationary finger at the other side of the spindle-pulley for holding such spindle-pulley and spindle when the lever is moved to slacken the driving-band, substantially as 70 set forth.

8. The combination, with the spindle-rail and spindle-socket, of a creel-bracket adapted to receive bobbins, a foot to the bracket setting against the spindle-rail and having a hole 80 for the bottom of the spindle-socket, and a nut upon such spindle-socket for securing the same and the creel-bracket to the spindle-rail, substantially as specified.

Signed by me this 13th day of February, 85
1889.

JOSEPH E. TYNAN.
